UNITED STATES PATENT OFFICE.

OSCAR I. SINGER, OF CHICAGO, ILLINOIS, ASSIGNOR TO SINGER BROS. & COMPANY, A COPARTNERSHIP.

TRAVELER'S HAND BAG OR SATCHEL.

Application filed November 18, 1921. Serial No. 516,065.

To all whom it may concern:

Be it known that I, OSCAR I. SINGER, a citizen of the United States, residing at Chicago, in the county of Cook and State 5 of Illinois, have invented certain new and useful Improvements in Travelers' Hand Bags or Satchels, of which the following is a specification.

This invention relates to improvements in 10 traveler's hand bag or satchel, and one of the objects of the same is to provide an improved bag of this character having means whereby shirts or other articles may be held within and against the side of the bag 15 whereby they may not only be protected and kept separate from the remaining articles within the bag, but will be capable of being freely removed without disarranging the remaining contents of the bag.

20 A further object is to provide an improved bag of this character having therein a flap or partition hingedly or foldably connected with the bag at the lower edge of the partition or flap, the upper edge of the 25 partition or flap being secured to the bag by suitable fastening devices, and the ends of the partition or flap being cut out or shaped so as to receive the folding in ends of the bag when the bag is closed, thereby 30 preventing injury to the partition or flap.

To the attainment of these ends and the accomplishment of other new and useful objects as will appear the invention consists in the features of novelty in substantially 35 the construction, combination and arrangement of the several parts hereinafter more fully described and claimed and shown in the accompanying drawing illustrating this invention and in which—

40 Figure 1 is a longitudinal vertical sectional view of a hand bag or satchel having this improvement applied thereto.

Figure 2 is a vertical sectional view on line 2—2, Figure 1.

45 Figure 3 is a side elevation of the partition or flap detached from the bag.

Figure 4 is a detail section view on line 4—4, Figure 2.

Referring more particularly to the drawing the numeral 10 designates generally a hand bag or satchel of the usual construction. The numeral 11 designates one of the frame members at the top of the bag and which members are pivotally connected at 50 their inner ends. The upper portions 12 of

the ends 13 of the bag are adapted to be folded inwardly as shown in Figure 1, when the frame members 11 are closed and when the frame members 11 are open the folded-in portions 12 will assume upright 60 positions and the frame members 11 may be held open in the ordinary and usual manner.

Within the bag is arranged a partition or flap designated generally by the reference 65 numeral 14 which may be constructed of any suitable material. The flap or partition 14 is connected as at 15 adjacent the bottom of one of the side walls 16 of the bag and may be secured in any suitable manner 70 such as by means of stitching or otherwise.

The flap 14 is preferably of a size substantially co-extensive with the side 16 of the bag or satchel, preferably both in length and height and is adapted to stand to one 75 side of the infolding portions of the ends of the bag and close to the adjacent wall. The upper portions of the ends of the flap or partition 14 are cut away or shaped as at 17 so as to receive the infolding portions 12 80 of the ends 13 of the bag when the latter is closed and when the flap is spaced from the side of the bag so that the flap or partition 14 will not be injured by the infolding ends and will not obstruct or prevent the fold- 85 ing in of these ends.

The flap or partition 14 is preferably provided with a hand hold 18 arranged along its upper edge and if desired, the edges of the partition or flap may be provided with a suitable re-enforcing band or binding 19, although this band or binding is not necessary.

The flap or partition is adapted to stand uprightly adjacent the side walls 16 of the 95 bag so that articles, such as shirts or the like may be placed between the partition and the wall 16 to keep them separated from the remaining articles in the bag and also to hold them in a position against the 100 side of the bag.

Any suitable means may be provided for holding the flap or partition in position such as fastening straps or tabs 20 which may be connected in any suitable manner 105 with the frame 11 and which carry adjacent one end thereof one member 21 of a separable fastening device such as a snap. The other member 22 of the fastening device being carried by the flap or partition 14. If 110

desired additional members or buttons 23 may be carried by the partition 14 and with which button the fastening device 21 is adapted to co-operate.

5 It will be seen that by detaching these straps or tabs 20 the partition 14 may be shifted by means of the hand hold 18 so as to permit the articles to be placed therebehind and when the articles are in position the 10 partition may be held by means of the tabs or straps 20. It will be manifest that the cut out portions 17 of the partition will permit the partition to assume a position somewhat spaced from the wall 16 of the bag 15 and at the same time will not interfere with the infolding portions 12 of the ends of the bag.

If desired pockets 24 may be provided on the outer face of the partition or flap 14 20 and also if desired additional infolding flaps 25-26 may be secured to the rear face of the partition or flap 14 so as to fold over the articles which may be placed against the inner face of the partition. These flaps 25-26 also serve as a means for separating the articles which may be placed between the partition and the wall 16 of the bag.

When it is not desired to store article behind the partition, the same may be held 30 against the side 16 of the bag by engaging the fastening devices 21 with the buttons 23.

Obviously any number of these buttons 23 may be employed and the straps or tabs 20 35 may be of a suitable length to correspond with the buttons.

While the preferred form of the invention has been herein shown and described, it is to be understood that various changes 40 may be made in the details of construction and in the combination and arrangement of the several parts, within the scope of the claims, without departing from the spirit of this invention.

45 What is claimed as new is:—

1. In combination, a hand bag or satchel, having infolding ends, a flap within the bag and secured by one extremity adjacent the bottom of one side of the bag and being of a 50 height substantially equal to the height of said side and co-operating therewith to form a storage space therebetween, said flap being also adapted to assume a position to one side of the infolding portions of the ends and 55 close to one side of the bag, and means detachably securing the upper edge of the flap adjacent the upper edge of the said side of

the bag, the ends of the flap being shaped for the reception of the infolding ends of the bag when the flap is spaced from the adjacent side of the bag. 60

2. In combination, a hand bag or satchel having infolding ends, a flap flexibly secured along one edge adjacent the bottom of one side of the bag and adapted to co-operate with said side of the bag to form an article receiving space therebetween, said flap being also adapted to assume a position to one side of the infolding portions of the ends and close to one side of the bag and means for detachably securing the upper edge of the flap to the said side of the bag, 65 the said flap being substantially co-extensive with the said side, the ends of the flap being cut out or shaped to receive the infolding ends of the bag when the flap is spaced from the adjacent side of the bag. 70

3. In combination, a hand bag or satchel having infolding ends, a flap flexibly secured within and along one edge adjacent the bottom of one side of the bag, said flap adapted to co-operate with said side of the bag to form an article receiving space therebetween and adapted to assume a position to one side of the infolding portions of the 85 ends of the bag, the flap being shaped so as not to interfere with the infolding ends when the flap is spaced from the adjacent side of the bag, means for detachably securing the upper edge of the flap to the said side of the bag, and one or more pockets carried by the outer face of the flap. 90

4. In combination, a hand bag or satchel having infolding ends, a flap flexibly secured within and along one edge adjacent the bottom of one side of the bag, said flap adapted to co-operate with said side of the bag to form an article receiving space therebetween and being also adapted to assume a position to one side of the infolding portions of the ends of the bag, the ends of the flap being shaped so as not to interfere with the infolding ends of the bag when the flap is spaced from the adjacent side of the bag, 95 means for detachably securing the upper edge of the flap to the said side of the bag, and one or more supplemental flaps carried by the first recited flap and foldable between the first said flap and the adjacent side of the bag. 100

105 In testimony whereof I have signed my name to this specification, on this 14th day of November, A. D. 1921.

OSCAR I. SINGER.
